UNITED STATES PATENT OFFICE.

JOHN GAMBLE, OF PHILADELPHIA, PENNSYLVANIA, ASSIGNOR TO GEORGE A. REACH,
OF PHILADELPHIA, PENNSYLVANIA.

CADDY-BAG.

1,122,721.

Specification of Letters Patent. Patented Dec. 29, 1914.

Application filed June 1, 1914. Serial No. 842,141.

To all whom it may concern:

Be it known that I, JOHN GAMBLE, citizen of the United States, residing at Philadelphia, Pennsylvania, have invented certain new and useful Improvements in Caddy-Bags, of which the following is a specification.

My invention is designed to add stiffness to a caddy bag without detracting from the general desirable feature of flexibility, and to this end I have inserted at intervals in the circumference of the bag stiffening strips extending from the top to the bottom, the stiffening strip having its end turned in and secured at the bottom.

In the accompanying drawing I have shown a caddy bag in elevation in Figure 1, and in Fig. 2 a vertical section. Figs. 2^a, 2^b, 2^c, show sectional details.

As ordinarily made up, there is a body section of suitable fabric as shown at A, and this is provided with a metallic ring section B at the upper end, the fabric being suitably secured to a leather top piece 25 which is turned inwardly around the metallic ring, being held thereto by a threading leather C, the leather piece being indicated at D. The bottom of the bag consists of a leather disk F forming the outer face, and 30 reinforced by a composition section f riveted to the leather disk and having a turned-down annular flange g to which is stitched a leather reinforced piece H. Within the

bag and forming the main bottom thereof is a veneered wood section k. I have found 35 it desirable to stiffen the bag longitudinally, and to this end I insert within channels formed by the material of the bag and leather strips L a steel member m, the upper end being riveted as shown at N, while its 40 lower end is bent at right angles passing between the wooden bottom and the composition member and secured by a rivet to the wood bottom. A series of these strengthening members is used, preferably three. 45 These members not only stiffen the bag longitudinally without detracting from the general flexibility of the bag, but tend to hold the parts together against undue strain, and generally render more durable 50 the bag and capable of resisting much more strain than is usual with the bags now in use.

I claim as my invention:—

A caddy bag comprising a body member, 55 an annular support at the top, a rigid bottom, flexible stiffening members rigidly secured to the bottom section, riveted at the top, and incased by the body material, substantially as described.

In testimony whereof, I affix my signature in presence of two witnesses.

JOHN GAMBLE.
